Primary Examiner — Lakiya G Rogers*Assistant Examiner* — John A Voytek(74) *Attorney, Agent, or Firm* — Fay Sharpe LLP(57) **CLAIM**

The ornamental design for a tire tread, as shown and described.

DESCRIPTION

FIG. 1 is a perspective view of a tire including the tire tread of the present application taken generally from the front and a first side of the tire;

FIG. 2 is a front view thereof;

FIG. 3 is a side view (the first side) thereof (the opposite side being identical);

FIG. 4 is an enlarged partial, perspective view taken generally from the front and the first side thereof;

FIG. 5 is an enlarged, partial front view thereof; and,

FIG. 6 is an enlarged, partial side view (the first side) thereof.

In the drawings, the broken lines depict portions of the tire that form no part of the claimed design. Likewise, the tire interior forms no part of the claim. Further, it is understood that the circumferential broken line closest to the elements shown in solid line represent boundaries of the claim. The tire tread is understood to repeat throughout the circumference of the tire.
